[57] CLAIM

The ornamental design for a portion of a shoe outsole, as shown and described.

DESCRIPTION

FIG. 1 is a perspective view of a portion of a shoe outsole showing my new design;

FIG. 2 is a bottom plan view thereof;

FIG. 3 is a profile view taken through line 3—3 of FIG. 2;

FIG. 4 is a profile view taken through line 4—4 of FIG. 2;

FIG. 5 is a profile view taken through line 5—5 of FIG. 2; and,

FIG. 6 is a profile view taken through line 6—6 of FIG. 2. The broken line showing of the remainder of the shoe is for illustrative purposes and forms no part of the claimed design.
